UNITED STATES PATENT OFFICE.

GEORGE RAYMOND AND ALBERT RAYMOND, OF CHICAGO, ILLINOIS.

GRINDING-MILL.

SPECIFICATION forming part of Letters Patent No. 354,228, dated December 14, 1886.

Application filed January 11, 1886. Serial No. 188,250. (No model.)

To all whom it may concern:

Be it known that we, GEORGE RAYMOND and ALBERT RAYMOND, citizens of the United States, residing at Chicago, in the county of Cook and State of Illinois, have invented certain new and useful Improvements in Grinding Mills, of which the following is a specification.

Our invention consists in certain combinations of parts and features of construction hereinafter fully described, and pointed out in the claims.

In the drawings hereto annexed, and which form a part of this specification, Figure 1 is a plan view of our machine looked at from above. Fig. 2 is a vertical cross-section of the same on the line 2 2, Fig. 1. Fig. 3 is a vertical cross-section of the stones, hopper, and adjoining parts on the line 3 3, Fig. 1; and Fig. 4, a detail of the step of the shaft.

We have shown our improvements as applied to a sweep-mill in this instance, but they are clearly applicable, in many respects, to mills of other constructions.

In the drawings, the sweep 1 is bolted to a master-wheel, 4, the latter being centrally pivoted upon the shaft 5, and giving motion to the pinion 6, cast in one piece with the gear-wheel 7, and rotating on the shaft 8, fixed in casting 9, attached to the bed-timbers 10 of the frame. The master-wheel has a projecting flange, 11, near its bottom, which engages with grooves cut in rotating pulleys 12 13 14 15, mounted on shafts fixed to the frame. These pulleys serve to steady the master-wheel vertically, and to partially support its weight. Motion is communicated from the gear-wheel 7 to pinion 16, formed in one piece with gear-wheel 17, which in turn communicates motion to pinion 18, mounted on the central shaft, 5. The hub of pinion 18 rests upon a projection from casting 9, in which the shaft 5 is set, and has at its lower side a beveled pinion engaging with a second beveled pinion on shaft 19, said shaft 19 being provided for the purpose of taking off surplus power from the mill to be used for driving other mills, or other purposes, and also to enable the mill to be driven by other than horse-power—as, for instance, by a steam-engine. The hub of pinion 18 has also an upward projection or sleeve, 20, which

affords a bearing for the central part of the master-wheel. Keyed upon this sleeve is a gear-wheel, 21, which meshes with pinion 22, rigidly mounted upon shaft 23, which carries upon its upper end a flanged casting, 24, supporting the lower millstone, 25. The shaft 23 passes through a casting, 26, bolted to the master-wheel, and carrying at its upper end the box or grinding-chamber 27.

The upper millstone is attached to the under side of a flat ring, 28, of such a size as to fit into box 27, said box being circular in form. The ring 28 has a circular flange, 29, projecting upward at right angles with its plane, 65 the circular opening within said flange being spanned by a narrow diametrical bridge, 30, said bridge being curved and having its convex side uppermost. The box 27 is provided with two diametrically - opposite flanges, 31 70 and 32', to one of which, 31, is pivoted a bar, 32, carrying the hopper 33, rigidly attached to it.

The lower part of the hopper is circular in shape, and of such a size as to be received 75 within the upwardly-projecting flange 29. To the flange 32' of the grinding-chamber is pivoted at 34 a rod, 35, the upper end of which is screw-threaded, and carries a hand-nut, 36, by means of which the free end of the bar 32 80 may be secured in position, said free end of the bar being provided with a slot, 37, for receiving the rod 35. Projecting from the under side of the bar 32 is a knob, 38, which bears upon the bridge 30, with the pressure 85 determined by the position of the end screw, 36.

It should be observed that the casting 26 has at its upper and lower ends two points of close bearing upon the shaft 23. The ring 28 is provided with springs 39, resting upon the upper edge of the box 27, and serving to keep the two millstones out of contact with each other when the mill is running empty.

The step 40, upon which the lower end of shaft 23 rests, is bolted to the master-wheel, 95 and is shown in detail in Fig. 4.

The mounting of the upper millstone and of the hopper which we have shown is not costly to make, is extremely simple, and is thoroughly efficient in operation. The plate 100 to which the upper stone is attached, having a central bearing only, can oscillate vertically

when any foreign substance comes between the faces of the stones enough to prevent injury to the grinding-surfaces.

We claim—

- 5 1. In a grinding-mill, the combination of a master-wheel, a casting bolted thereto on one side of its center, a millstone supported on said casting, a shaft journaled in the said casting and geared to be driven by the master-wheel, a second millstone carried by the said shaft, and a central fixed shaft for the master-wheel, substantially as and for the purpose set forth.
- 15 2. In a grinding-mill, the combination of a master-wheel, with a casting made fast thereto, a millstone adjustably mounted upon said casting, a shaft and a second millstone mounted thereon, and a step fixed to the master-wheel and supporting the shaft, substantially as and 20 for the purpose set forth.

3. In a grinding-mill, the combination of a grinding-chamber, a running-stone revolving therein, a plate and a bed-stone attached thereto lying loosely upon said running-stone, said plate being provided with a central aperture 25 for the feed of grain, and a diametrical bridge across said aperture, a bar provided with a knob resting freely upon the upper surface of said diametrical bridge, and means for varying the pressure of said point upon said bridge, 30 and thereby the grinding of the mill, substantially as described.

GEORGE RAYMOND.
ALBERT RAYMOND.
